UNITED STATES PATENT OFFICE.

STEVEN KRAMER, OF DETROIT, MICHIGAN.

FLAME-EXTINGUISHING DEVICE.

1,159,960.

Specification of Letters Patent.

Patented Nov. 9, 1915.

Application filed May 14, 1915. Serial No. 28,200.

To all whom it may concern:

Be it known that I, STEVEN KRAMER, a citizen of the United States of America, residing at Detroit, in the county of Wayne and 5 State of Michigan, have invented new and useful Improvements in Flame-Extinguishing Devices, of which the following is a specification.

This invention relates to certain novel and 10 useful improvements in flame extinguishing devices for lamps of the wick type and has particular application to a manually operable extinguishing device.

In carrying out the present invention, it is 15 my purpose to provide an extinguishing device for kerosene lamps which may be operated manually to smother the flame issuing from the wick, thereby eliminating the necessity of removing the chimney and blowing 20 out the flame.

It is also my purpose to improve and simplify the general construction of flame extinguishers and to provide a flame extinguishing device which may be readily and quickly 25 applied to any type of wick lamp and which may be removed therefrom whenever desired.

With the above and other objects in view, 30 the invention consists in the construction, combination and arrangement of parts hereinafter set forth in and falling within the scope of the claims.

In the accompanying drawing; Figure 1 is a perspective view of the burner of a 35 kerosene lamp equipped with a flame extinguisher constructed in accordance with the present invention, parts being shown in section. Fig. 2 is a vertical sectional view through the same. Fig. 3 is a horizontal sectional view therethrough. Fig. 4 is a perspective view of a detail of the invention. Fig. 5 is a similar view of another detail. Fig. 6 is a like view of one of the shutters.

Referring now to the drawing in detail, 45 1 designates the burner of a kerosene lamp, such burner embodying the usual wick tube 2.

My improved flame extinguisher comprises a base or support in the form of a strip of metal 3 formed centrally with a 50 longitudinal slot 4 adapted to receive the wick tube 2. The opposite ends of the strip 3 are stamped to provide upwardly extending arms 5, 5 disposed at the edges of the wick tube respectively.

6, 6 designate shutters, each comprising a 55 back plate 7, flanges 8, 8 formed at the end edges of the plate and projecting outwardly therefrom at right angles thereto and a flange 9 formed on the top edge of the plate and projecting outwardly therefrom at right 60 angles thereto and having the ends thereof secured to the adjacent ends of the side flanges 8. The remaining ends of the side flanges 8 project beyond the adjacent side edge of the plate as at 10 and are formed 65 with axially alining holes 11. These shutters 6, 6 are disposed at the opposite sides of the wick tube 2 and the openings 11 in the downwardly projecting end portions 10 of the side flanges 8 of each shutter aline with 70 openings formed in the arms 5 respectively and passed through these alining openings are pivot pins 12. Thus, the shutters 6, 6 are pivotally supported upon the arms 5 at the opposite sides of the wick tube and when 75 the shutters are moved forwardly toward each other the confronting edges of the flanges 8 and 9 thereon engage each other and inclose the lighted end of the wick, thereby smothering the flame. 80

In the present instance, the opposite side edges of the plate or support 3 are formed to provide pairs of ears 13, 13 respectively, and an S-shaped lever 14 is pivoted between its ends between each pair of ears 13. The 85 upper extremities of the S-shaped levers 14 are connected through the medium of links 15 with the shutters 6, 6 respectively, while the lower ends of the S-shaped levers terminate in proximity to the adjacent side of the 90 wick tube. Suitably secured to the lower portion of the burner is a supporting strip 15' fastened to the base centrally of its ends and pivoted upon the strip 15' at opposite sides of the adjacent arm 5 are operating 95 levers 16 capable of swinging movement and having the inner ends thereof pivotally connected to the lower ends of the S-shaped levers 14 respectively and the outer ends formed with finger holds 17. 100

18 designates a spring interposed between the levers 16 outwardly of the strip 15 and acting to hold the outer ends of such levers spaced apart.

In practice, the spring 18 acting upon the 105 levers 16 acts, through the levers 14 and links 15, to hold the shutters 6 in open position and when it is desired to swing the

shutters to envelop the flame so as to extinguish the latter, the portions 17 of the levers 16 are grasped by the hand and drawn together, thereby moving the lower ends of the levers 14 outwardly and the upper ends of the levers inwardly and in the inward movement of the upper ends of the levers, the links 15 act to swing the shutters together and so extinguish the flame.

10 While I have herein shown and described the preferred form of my invention by way of illustration, I wish it to be understood that I do not limit or confine myself to the precise details of construction herein described and delineated, as modification and variation may be made within the scope of the claims without departing from the spirit of the invention.

I claim:

20 1. A flame extinguishing device for kerosene lamps comprising a support carried by the wick tube, arms upstanding from said support at the edges of the wick tube, shutters each having the side edges thereof pivoted to said arms respectively and movable toward each other to envelop the flame, means for moving said shutters, manually operable levers pivotally mounted upon said support, and connections between said levers and shutters whereby the latter may be swung together in the operation of said levers.

2. A flame extinguishing device for kerosene lamps comprising a support carried by the wick tube, arms upstanding from said support at the edges of the wick tube, shutters each having the side edges thereof pivoted to said arms respectively and movable toward each other to envelop the flame, means for moving said shutters, manually operable levers pivotally mounted upon said support, connections between said levers and shutters whereby the latter may be swung together in the operation of said levers, and

a spring acting upon said levers to hold the shutters normally open.

3. A flame extinguishing device for lamps comprising a support carried by the wick tube and detachable therefrom, arms upstanding from said support at the edges of the wick tube, shutters each having the side edges thereof pivoted to said arms respectively and movable toward each other to envelop the flame, S-shaped levers pivotally connected between their ends to the respective side edges of said support, link connections between the upper ends of said S-shaped levers and the respective shutters, and hand operated levers connected to the lower ends of said S-shaped levers and operable to swing the S-shaped levers to move said shutters into engagement with each other.

4. A flame extinguishing device for lamps comprising a support carried by the wick tube and detachable therefrom, arms upstanding from said support at the edges of the wick tube, shutters each having the side edges thereof pivoted to said arms respectively and movable toward each other to envelop the flame, S-shaped levers pivotally connected between their ends to the respective side edges of said support, link connections between the upper ends of said S-shaped levers and the respective shutters, hand operated levers connected to the lower ends of said S-shaped levers and operable to swing the S-shaped levers to move said shutters into engagement with each other, and means acting upon said hand levers to hold the shutters normally in open position.

In testimony whereof I affix my signature in presence of two witnesses.

STEVE KRAMER.
